HAND GRIP FOR AN AUTOMOBILE

James A. Huggins, Birmingham, Mich., assignor to Chrysler Corporation, Highland Park, Mich., a corporation of Delaware

Filed May 23, 1960, Ser. No. 60,680

Term of patent 7 years

(Cl. D10—8)

Fig. 1 is a side view of a hand grip for an automobile embodying my new design;

Fig. 2 is a rear elevational view thereof; as viewed from the right of Fig. 1;

Fig. 3 is a perspective view of a portion of an automobile showing my hand grip in side elevation on a reduced scale; and

Figs. 4, 5, 6, 7 and 8 are sectional views taken on the lines 4-4, 5-5, 6-6, 7-7 and 8-8, respectively, of Fig. 1.

The broken line portion of the automobile is shown for illustrative purposes only.

I claim:

The ornamental design for a hand grip for an automobile, substantially as shown and described.
